Primary Examiner — Lilyana Bekic*Assistant Examiner* — Sharon S Oum(74) *Attorney, Agent, or Firm* — Kirschstein, Israel, Schiffmiller & Pieroni, P.C.(57) **CLAIM**

The ornamental design for a bottle, as shown and described.

DESCRIPTION

FIG. 1 is a perspective view of a bottle according to my new design.

FIG. 2 is a top plan view thereof.

FIG. 3 is a side elevational view thereof, all side elevational views being identical.

FIG. 4 is a bottom plan view thereof; and,

FIG. 5 is a sectional view thereof, as taken along the line 5-5 of FIG. 3.

The dash-dash broken lines shown in the drawings are included for the purpose of illustrating environmental structure and form no part of the claimed design.

The dot-dot-dash broken lines shown in the drawings define the boundary of the claimed design and form no part thereof.
